UNITED STATES PATENT OFFICE

160,102

FORK OR OTHER ARTICLE OF FLATWARE

Harry A. Malinowski, Meriden, Conn., assignor to Amston Silver Co., Inc., Amston, Conn., a corporation of Connecticut

Application May 25, 1949, Serial No. 2,867

Term of patent 14 years

(Cl. D54—12)

To all whom it may concern:

Be it known that I, Harry A. Malinowski, a citizen of the United States and residing at Meriden, in the county of New Haven and State of Connecticut, have invented a new, original, and ornamental Design for a Fork or Other Article of Flatware, of which the following is a specification, reference being had to the accompanying drawings, forming part thereof.

In the drawings, Fig. 1 is a front elevational view of a fork, showing the essential features of my new design in full lines. Figs. 2 and 3 are respectively sections taken along lines 2—2 and 3—3 of Fig. 1.

I claim:

The ornamental design for a fork or other article of flatware, as shown and described.

HARRY A. MALINOWSKI.
